DESTRUCTIVE HYDROGENATION OF DISTILLABLE CARBONACEOUS MATERIALS

Mathias Pier, Heidelberg, and Wilhelm Rumpf, Ludwigshafen-on-the-Rhine, Germany, assignors, by mesne assignments, to Standard I. G. Company, Linden, N. J., a Corporation of Delaware

Application October 1, 1929, Serial No. 396,486,
and in Germany October 9, 1928

2 Claims. (Cl. 196—116)

This invention relates to improvements in the destructive hydrogenation of distillable carbonaceous materials.

When in the destructive hydrogenation of distillable carbonaceous materials and in particular of carbonaceous materials in the liquid form, such as coal sludges, tars, mineral oils, extraction, distillation and conversion products thereof and the like with hydrogen or gases containing or supplying hydrogen, the reaction vessel is heated from the outside, it is found that although generally speaking no attack of the metal walls by hydrogen occurs in the presence of oil, it sometimes nevertheless happens that tubes crack and are attacked by the hydrogen. The probable reason for this is that in consequence of local superheating or in consequence of some other cause, a certain amount of a coke crust has been deposited in some part of the apparatus and this hinders the transference of heat from the metal walls to the materials under treatment, for example coal sludge or oil. Consequently a strong heating of the wall at these places occurs even when the hot gases are not at too high a temperature. At these places cracking of the tubes occurs, probably assisted or caused by an attack of hydrogen on the crude materials. It has already been proposed to employ heating media which have a temperature which is not appreciably higher than the reaction temperature. This, however, leads to inconveniences in heat technique, since in this case heating surfaces having a very considerable area are required.

We have now found that heating media which have a temperature substantially higher, at least 100° centigrade higher, than the reaction temperature can be employed, provided that they do not have a temperature above 800° centigrade, when provision is made for a uniform flow of heat from the heating medium to the materials under treatment of the materials to be treated. In this manner the materials may be pre-heated prior to being subjected to destructive hydrogenation or may be heated during the destructive hydrogenation. The said materials are hereinafter referred to for the sake of brevity as the charge. For example, in order to prevent a surpassing of the maximum temperature hereinbefore mentioned, the effluent heating gases, which have already been cooled to a certain extent, may be mixed with a quantity of flame gases sufficient to heat them up to the desired temperature and recycled. The superheating

or the formation of injurious coke crusts can also be prevented by immediately removing the coke which is formed at some place or the other by means of special apparatus. Care should be taken that no rough places are present on the inner walls of the tubes or vessels to which coke may attach itself or at which exothermic chemical side reactions may occur.

Another method of working in order to prevent local superheating is by not allowing the heating gases, which in this case may be at a temperature above 800° centigrade, to come into direct contact with the walls of the tubes or vessel but to arrange a protecting tube between the same. In the intermediate space between two tubes the heat is distributed uniformly and is then also transferred uniformly to the tubes. It is of particular advantage in some cases to work with vertical tubes because then the oil is uniformly distributed over the inner surfaces of the said walls.

By the process in accordance with the present invention it is possible to employ comparatively less resistant material for the walls of the apparatus, for example weakly alloyed steel. It is also advantageous to provide the parts which are heated to a relatively high temperature with special jackets of resistant material, whilst the other parts may be constructed of less expensive material.

The process according to the present invention may be carried out under any of the conditions of temperature and pressure suitable for destructive hydrogenation for example at elevated pressure, and catalysts in particular those immune from poisoning by sulphur, may be employed if desired, and in particular catalysts comprising cobalt or a metal from the sixth group of the periodic system, such as molybdenum, tungsten or chromium as such or in the form of its compounds.

The temperatures of the reaction materials in the said destructive hydrogenation process will usually range between about 300° and 600° C. and may in some cases attain 700° C., but preferably temperatures of between about 380° and 550° C. are employed.

The pressure employed will usually exceed atmospheric. Thus for example pressures of 20 or more atmospheres may be employed, and preferably higher pressures, such for example as 50, 100, 200, 300, 500, 600, 1000, 2000, 3000, 5000 or even more atmospheres are made use of in the process.

Hot gases from any source may be employed as heating gases, such for example as flame gases, hot producer gas and the like.

The nature of the invention will be further described with reference to the accompanying drawings, Figures 1 and 2 being vertical sections of a modification of the apparatus at right angles to each other, and Figures 3 and 4 being a vertical section and a plan of a further modification of the apparatus having vertical pipes, which drawings illustrate arrangements of apparatus according to this invention, by way of example, but the invention is not restricted thereto. In Figures 1 and 2 *o* is a chamber and *a* are burners for the combustion of gases therein. *b* is a passage in the wall of the said chamber and *c'* are openings for the admission of recycled gases from the said passage into the chamber *o* wherein the latter gases are mixed with the said gases of combustion. *e* is a larger chamber containing a system of coils *p* and separated from the chamber *o* by the baffle plate *d'* around which the mixture of gases from the chamber *o* passes into the chamber *e*. *f* is a pipe for the introduction into the coil system *p* of the materials to be subjected to destructive hydrogenation. *g* is a pipe for the removal of the said materials from the tube system. *h* is an opening for the removal of the heating gases from the chamber by way of the flue *w*. *i* is a gas pump for maintaining the gases issuing at *h* in circulation. *m* is a pipe for recirculating the heating gases and *n* is a branch pipe controlled by the valve *k* for the removal of gases from the cycle.

Referring first to Figures 1 and 2 of the accompanying drawings, flame gases coming from a burner *a* are mixed at *b* with circulating heating gases, which have already been employed for heating, in order to reduce the temperature of the said flame gases; they then pass through numerous openings *c*, pass round a baffle plate *d* and finally enter into a closed chamber *e* in which are arranged the conduit pipes *p* for the reaction materials. Tar and hydrogen, for example, enter the coil of pipes at *f* at room temperature and under a pressure of 200 atmospheres, and leave the same at *g* with a temperature of about 450° C. The upper windings of the pipes have a special insulation, which is indicated by dotted lines, to protect them from superheating. The heating gases leave the heating chamber *e* at *h*, and are circulated by a gas pump *i*. They then pass either into the flue through the valve *k*, or back into the chamber at *b*.

A mixture of tar and hydrogen is introduced under a pressure of about 200 atmospheres and at room temperature through the pipe *f* into the coil *p* and is heated therein to a temperature of about 450° C. at which temperature it is drawn off at *g* and passed into a high pressure reaction vessel not shown in the drawings and containing a catalyst prepared from tungstic acid and magnesia. About 90 per cent of the tar is in this way converted into low boiling hydrocarbons of gasoline character. No deposition of coke takes place in or on the preheating coil owing to the fact that the temperature of the flame gases has been reduced to about 650° C. and that a very uniform heating of the mix-

ture of tar and hydrogen takes place.

Turning now to Figures 3 and 4, *a* is a burner in which gases are burnt. The hot flame gases thus obtained are mixed in the chamber *o* with gases, which have been recycled through the pipe *m* and which are introduced into the said chamber by way of the passages *b*, and the gas mixture thus obtained is introduced through the numerous openings *c* into the closed chamber *e* containing the coil *p*, through which a charge of materials which is to be subjected to destructive hydrogenation is passed. The heating gases issue from the said chamber *e* through the opening *h* and are passed on to the circulating gas pump *i*, from which the said gases may either be withdrawn through the pipe line *n* controlled by the valve *k*, or the said gases may be recycled through the pipe line *m*. The materials which are to be heated and to be subjected to destructive hydrogenation are introduced to the coil *p* by way of the pipe *f* and removed by the pipe *g*. A mixture of crude oil and hydrogen is introduced under a pressure of 200 atmospheres and at room temperature by way of the pipe *f* to the coil *p*, wherein the said mixture is preheated to a temperature of 450° C., with which it leaves the said chamber at *g*. The heating gases have a temperature of about 800° C. and the gases leaving the chamber at *h*, which have been employed for heating, have a temperature of about 380° C. The preheated mixture of crude oil and hydrogenating gas is passed directly from *g* into a reaction vessel containing a catalyst prepared from molybdic acid and zinc oxide and is hereby converted for the most part into liquid hydrocarbons of low boiling point of gasoline character.

What we claim is:—

1. In the process for destructively hydrogenating bituminous materials with hydrogen at a temperature and pressure suitable for destructive hydrogenation and in which the hydrogen and bituminous material react with the evolution of heat and are passed at the pressure desired for the destructive hydrogenation through a tortuous confined pathway heated to the destructive hydrogenation temperature, the method of avoiding localized superheating in said confined pathway which comprises heating said confined pathway by a mixture consisting of flame gases diluted with cool gases of combustion to give said mixture a temperature at least 100° C. higher than the temperature of the destructive hydrogenation, but below 800° C.

2. In the process for destructively hydrogenating bituminous materials with hydrogen at a pressure of about 200 atmospheres and at a temperature suitable for destructive hydrogenation and in which the hydrogen and bituminous material are passed at said pressure through a tortuous confined pathway in which they are heated to about 450° C., the method of avoiding localized superheating in said confined pathway which comprises heating said confined pathway by a mixture consisting of flame gases diluted with cool gases of combustion to give said mixture a temperature of about 650° C.
